ROTARY PUMP

Gerald J. Harman and Arthur M. Briggs, Los Angeles, Calif., assignors to Harman Pacific Company, Los Angeles, Calif.

Application March 19, 1932, Serial No. 599,968

3 Claims. (Cl. 103—42)

Our invention relates to rotary pumps and more particularly to improvements whereby the blades are held yieldingly in engagement with the cylinder wall by means of expansion rings placed within the inside blade circle at each end of the rotor, thus insuring free movement of the blades at light, even tension between the expansion rings and the pump cylinder, and insuring a better seal between said blades and the cylinder wall.

Another object of our invention is to provide in a rotary pump an improved by-pass valve between the intake and the discharge chambers of the pump, whereby when the discharge outlet is closed or blocked in any way, said by-pass will yield and permit the discharge into the intake passageway, thus providing a safety element in connection with a rotary pump.

Other objects and purposes of our invention will be clear from the following description thereof, taken in connection with the accompanying drawing in which—

Figure 1 is a side or edge elevation of a rotary pump embodying our invention;

Figure 2 is a front elevation of said rotary pump, with parts removed and shown in section to show the interior construction and arrangement;

Figure 2^a is a sectional view taken on line 2—2 of Fig. 2;

Figure 3 is a sectional view in detail showing a modified form of by-pass valve mechanism; and

Figure 4 is a plan view thereof.

Referring in detail to the drawing, our rotary pump body 5, has a central bore or cylinder chamber 6, with passageways 7 and 8 connecting with the opposite sides thereof, as indicated, and in the usual and well known manner, one of said passageways serves as intake and the other as discharge.

Mounted through said cylinder chamber 6 is a shaft 9, on which is a rotor 10, eccentrically positioned relative to said cylinder chamber, with radially disposed blades 11, 11, having their outer edges in sealing engagement with the cylinder wall in a well known manner. An expansion ring 12 is provided around said shaft and bearing against which expansion ring is the inner edge or end of each of said blades, said expansion ring floating in a chamber formed in the end of the rotor and designated 10'. It will be understood, as seen in Fig. 2^a, that the rotor has formed in each end one of these expansion ring chambers 10' and that there is an expansion ring at each end, against which the opposite ends of each

blade bear, whereby each blade is yieldingly pressed outwardly at each end. The tension is uniform on each blade and each blade is held against the wall of the cylinder with a uniform pressure, for the expansion rings move bodily around in their chambers in the ends of the rotor as the blades move in and out radially during the rotation of the rotor.

Mounted on the body is a by-pass body member 13, having a partition 14, dividing it into two passageways 15 and 16, which register with the passageways 7 and 8, respectively. A top cap 17 is mounted on said member 13, with pipe connections, as 18 and 19, for inflow and exhaust. Screwed into the partition 14 is a valve seat cage 20, within which is valve 21, seating at 22, in said cage 20, and normally held closed by means of a coiled spring 23, the outer end of which connects with a tension rod or bolt 24, through a plug 25, and provided with a nut 26, as clearly seen in Fig. 2. By adjustment of said nut and bolt, the tension of the spring can be regulated.

Said by-pass body member 13, it will be noted, is interposed between the pump body 5 and the cap 17, much as a gasket would be interposed therebetween and inasmuch as it is self-contained or a complete unit, it is made so that it can be reversed so as to change the direction of operation of the spring pressed valve 21. Thus our device can be inserted when a by-pass is desired, or detached, and can be turned to reverse the operation of the by-pass valve. The cap 17 will fit the body when the by-pass body member is removed.

In Figs. 3 and 4, we have shown a modified form of valve for the by-pass. In these views the partition is designated 14', the valve 21' with seat at 22', said valve having its inner portion in the form of a cross, as seen in light broken lines in Fig. 4, with a cam ring 27 around the opening through said partition, said cam ring having two circumferentially extending inclined cam edges, as seen, with a flat spring member extended across the same and designated 28, and secured in its middle to the crossed portions of said valve 21' by means of a top plate 29 and screws 30, as seen in Fig. 4. Said spring 28 yieldingly holds said valve closed, but when pressure on the spring side of the valve is increased beyond normal, said spring will yield and permit said valve to open sufficiently to permit passage through the partition from one side to the other.

Thus we have provided an effective by-pass for a rotary pump which will operate under extreme or excessive pressure to relieve the pump and dis-

charge into the inflow passageway as the rotor revolves.

The pump body has suitable side plates, as 5', 5", with the usual bearing and bushing, designated 31 and 32, respectively, for the shaft 9.

While we have shown and described the practical embodiment of our invention, we are aware that changes can be made as to details of construction and arrangement without departing 10 from the spirit thereof, and we do not, therefore, limit the invention to the showing made, except as we may be limited by the hereto appended claims.

We claim:

15 1. A rotary pump including a pump body, a cap member having means for connecting intake and discharge pipes thereto, said cap being adapted to fit upon said body to open communication between said pipes and said pump body, and a 20 unitary, by-pass mechanism adapted to be interposed between said pump body and said cap member gasket-like to provide communication between said pipes outside of said pump body, said by-pass mechanism including a spring-pressed 25 valve.

2. A rotary pump of the character shown and

described and including in combination a pump body with rotor therein, a cap for said body having intake and discharge pipes connected therewith, and a by-pass mechanism, self-contained and adapted to be interposed between said body and said cap and to be clamped therebetween and having a spring-pressed valve therein adapted to control communication between said intake and discharge pipes between the pump and said cap, said by-pass mechanism being reversible whereby to reverse the direction of flow between 85 said intake and said discharge pipes outside of said pump.

3. In combination, a cylinder body to receive and discharge fluid, inflow and outflow pipes, means in said body for drawing fluid in and forcing it out, means for connecting said pipes together and to said cylinder body, and a by-pass mechanism adapted to be clamped between said cylinder body and said means gasket-like, said by-pass mechanism being reversible as to position, whereby to change the direction of flow through said by-pass.
